[57] **CLAIM**

I claim the ornamental design for a golf putter head, as shown and described.

DESCRIPTION

FIG. 1 is a front elevation view of the invention, showing my new design;

FIG. 2 is a top plan view of the golf putter head of the invention;

FIG. 3 is a rear elevation view of the golf putter head of the invention;

FIG. 4 is a left side elevation view of the golf putter head of the invention;

FIG. 5 is a right side elevation view of the golf putter head of the invention; and,

FIG. 6 is a bottom plan view of the golf putter head of the invention.

The portion of the golf club handle shaft shown in dashed lines in FIGS. 1 through 5 is not a part of the claimed design and is shown for context and orientation. The golf putter head of the invention is laterally symmetrical, with the left side and the right side being mirror images of each other.
